MACHINE FOR CUTTING ROAD SURFACES

Earl A. Lenker, Norristown, Pa.

Application November 4, 1954, Serial No. 466,845

4 Claims. (Cl. 94—39)

This invention relates to a machine for cutting road surfaces in order to prepare them for suitable repairs although it can be used also as a simple planer for smoothing off irregularities if so desired. However, the main features of the invention are related to the preparation of damaged portions of so-called "blacktop" roads whereby repairs can be effected having neat joints with the undamaged portions and also with the repaired surfaces conforming smoothly to the curvature, inclination or configuration of the original road.

The principal object of the invention is to provide a machine by means of which a hole in the road or an irregularity in the road can be cut out to provide clean edges into which the patching material can be placed and brought to contour with the balance of the road. In much of the road repair work required today it is necessary that the cavity be prepared so that its bottom inclines or tapers toward the good surface of the road while at the same time all of the deeper portions of the cavity are provided with the clean edges already referred to. My invention has for its object the preparation of such cavities.

A further object of my invention is to provide a machine of the character described which is of relatively small size and correspondingly light weight so that it can be readily transported, easily maneuvered in service by a single man and inexpensively operated and maintained.

Still another object of the invention is to provide very simple mechanism for accomplishing the results desired, which mechanism can be quickly adjusted to suit the requirements of any individual job.

How the foregoing objects, together with such other objects as may appear hereinafter or are incident to my invention, are attained is illustrated in preferred form in the accompanying drawings wherein

Figure 1 is a side elevation of my improved machine; Figure 2 is a plan view of Figure 1;

Figure 3 is a vertical section taken as indicated by the line 3—3 on Figure 1;

Figure 4 is a diagrammatic front elevation of the principal features of construction but omitting the engine and driving mechanisms for the sake of greater clarity. In this view the frame members of the machine are shown in the relative positions they will occupy in order to prepare a cavity for the reception of repair material; and

Figure 5 is a diagrammatic side elevation of the structure shown in Figure 4.

As will be seen by an inspection of the drawings, the principal structural features of my improved machine are as follows:

(1) A main frame MF composed of an open box-like section 5 and a forward U or channel shaped section 6 which is pivoted or jointed to the section 5 by means of a pair of oppositely disposed bolts 7. The extension 6 of this main frame is provided with a pair of front wheels 8 mounted upon axes 9 around which the rear end of the section 6 can swing slightly as the joint 7 is raised

2

or lowered in accordance with the description to follow. The section 5 of the main frame has a pair of rear wheels 10 mounted on the axes 11 and this section 5 can swing on the axes 11 as the joint 7 is lowered or raised. At the rear the section 5 of the main frame is provided with the operating handle bar 12 by means of which the operator maneuvers the machine. At the forward end a scissors toggle 13 reacts between the front member 6a of the forward extension and a transverse channel 5a of the rear or box section of the main frame. This scissors toggle can be extended or contracted by means of a screw member 14 operated by a wheel 15 in a manner well understood in this art, there being a block 16 which moves along the thread 14 as the wheel 15 is turned. The forward members of the scissors are mounted to pivot around a pin 17 and the rear members around a pivot 18 in order to accommodate changes in angular relationships between the parts as the screw is expanded or contracted. When the scissors is contracted the forward portion 6a of the extension 6 will, of course, be raised and the jointed or pivoted portion 7 will be lowered, the side arms 6 of the forward extension swinging on the axes 9 as already mentioned.

(2) An inner open box-like frame IF which is trunnioned on the transverse members 5a and 5b of the outer frame upon fore and aft pins 19, whereby the inner frame can be tilted laterally or side-wise with respect to the outer frame, such tilting being provided for by means of another scissors toggle 20 which reacts between the upper side frame member 5c of the main frame and a lower inner side frame member 21 of the inner frame IF. To this end suitable inwardly projecting brackets 22 on the member 5c and outwardly projecting brackets 23 on the member 21 are provided. The scissors toggle 20 is operated by the screw bolt 24. The pillow blocks 25 and 26 ride along the screw and the pillow block 26 abuts against the stop 27. The screw projects rearwardly and is provided with a handle 24a by means of which it can be turned to effect the required adjustment.

As will be seen the forward portion 28 of the inner frame projects forwardly to a point slightly beyond the joints 7 of the main frame. Between suitable bracket members 29 is trunnioned a cutting cylinder 30, the members 29 and the cylinder 30 being carried by the forward lower corners of the inner box-like frame. Toward the rear a power device, preferably a gasoline driven motor 31, is carried by the inner frame upon a pair of cross members 32. At a point between the engine and the cutting cylinder a counter-shaft 33 is also mounted in the side members of the inner frame, on each end of which is a driving pinion 34. Similar driving pinions 35 are provided on each end of the cutting cylinder axis, all of said pinions being secured to the shafts upon which they are mounted. A chain 36 drivingly connects the corresponding pinions at each end of the cutting cylinder. The counter-shaft 33 is also provided with a large gear 37 which is chain driven by means of the chain 38 actuated by the gear 39 on the crankshaft of the engine. A clutch mechanism 40 operated by a clutch handle 41 is provided for connecting the engine to the driving mechanism. As will be noted, the engine, the cutting cylinder and all of the driving parts which connect the two are carried on the inner frame IF so that they all tilt with the frame when the frame is rocked on its trunnions 19 so as to change the angular relation of the cutting cylinder 30 with respect to the surface of the road.

The functioning of the machine is probably best illustrated in the diagrammatic views of Figures 4 and 5. In these views the road surface appears at R. At the point where repairs are needed which require cutting the surface to form a suitable cavity for reception of the

repair material, it will be assumed that the edge 42 marks the point where a hole has developed. This point should be cut to a clean edge and the bottom should be inclined as at 43 so that when the cavity is ready for reception of the repair material it will slope upwardly from the cut at 42 to the normal surface of the road at 44. There are, of course, situations where just the opposite tilt will be required or even where both ends of the cutting cylinder are projected downwardly into the surface of the road to make clean edges at both sides. However, I have found that in most instances a tapered cut will generally suffice and naturally such a cut will save a considerable amount of repair material. The machine is pushed along much in the manner of a lawn mower and the angular position of the cutting cylinder 30 can be quickly changed by the operator through the medium of the scissors toggle 20 and the handle 24a. The elevation of the cutting cylinder 30 can be quickly and easily adjusted by means of the scissors toggle 13 at the forward end of the machine. Through the medium of the two toggles any desired cylinder level and inclination can be quickly established and when the cutting cylinder is rotated the teeth 30a thereon will chew away the surface quickly and accurately and in far less time than has been possible with any machine or manual operation with which I am presently familiar.

I claim:

1. A machine for cutting road surfaces comprising a main frame, a wheel at each side of said main frame secured thereto in axial alignment at a point behind the forward end thereof; a forward extension frame, a wheel at each side of said extension frame secured thereto in axial alignment at a point in front of the rear end thereof; said frames being pivotally jointed together at a point between the axes of said wheels; each of said frames being adapted to swing around the axis of its wheels and said pivoted joint being adapted to move

upwardly and downwardly during such swinging movement of the frames; means for effecting such upward and downward movements; an inner frame trunnioned on the main frame to rock laterally with respect thereto; a cutting cylinder rotatably carried by the inner frame upon an axis which extends transversely of the machine; means for transversely rocking the inner frame on its trunnion mounting whereby to alter the angular relation of the cutting cylinder to the surface of the road; and power means for rotating the cutting cylinder.

5 2. A machine for cutting road surfaces comprising an outer frame mounted on front and rear wheels, said frame having a front section and a rear section pivotally jointed together at a point between the front and the rear wheels, 15 means for lowering or raising said joint, an inner frame carried by and trunnioned on one section of the main frame for lateral tilting movement with respect to the main frame, a transversely arranged cutting cylinder rotatably carried by the inner frame in the vicinity of 20 said joint, means reacting between the two frames for tilting the inner frame whereby to alter the angular relation of the cutting cylinder to the surface of the road and power means for rotating the cutting cylinder.

25 3. A machine according to claim 2 wherein the power means is carried by the inner frame so as to move therewith.

4. A machine according to claim 3 wherein the power means for driving the cylinder includes a chain and sprocket drive at each end of the cutting cylinder.
